ABSTRACT

The information carrier is wound on a reel which is contained in a cartridge of either of first and second types. Each of the cartridges has locating and fixing surfaces specific to the type of cartridge. The reel in the cartridges of said first type has a flange. The reel in the cartridges of the second type has a central bore. The cartridges of the second type have a wall formed with an aperture aligned with said bore. The information carrier on said reel has a leading end. The appliance comprises first locating and fixing means adapted to engage said locating and fixing surfaces of any cartridge of said first type so as to hold said cartridge of said first type in an operative position on said appliance, second locating and fixing means adapted to engage said locating and fixing surfaces of any cartridge of said second type so as to hold said cartridge of said second type in an operative position on said appliance, threading means operable to mechanically move said leading end of said information carrier in a cartridge of either of said first and second types when said cartridge is held in said operative position, first reel-driving means adapted to cooperate with said flange and operable to drive said reel in a cartridge of said first type when said cartridge is in said operative position, and second reel-driving means comprising a mandrel adapted to extend through said aperture into engagement with said bore of a reel of a cartridge of said second type when said cartridge is in said operative position. The second reel-driving means are operable to drive said reel in said cartridge of said second type.

INFORMATION-PROCESSING APPLIANCE FOR USE
WITH A STRIPLIKE INFORMATION CARRIER
CONTAINED IN A CARTRIDGE

Various types of cartridges have already been proposed for use with motion-picture projectors for substandard film. The cartridges of each of these types differ in capacity and are intended to receive film wound on supply reels. The cartridges of the types which have been proposed so far differ in cartridge size, cartridge form, means required to drive the supply reels in the cartridges, means required to hold the cartridges on a projector, etc. For a manufacturer of projectors, this means that in selecting a design for his projectors he must choose one of these types of cartridges. For a user of a projector, this means that he can use only cartridges of that type for which the projector is designed. Hence, a user of a projector either cannot project films, e.g., rented films, which are supplied in cartridges for which his projector is not designed, or he must procure another projector designed for use with cartridges of a second type. This is a serious disadvantage for the users of substandard film projectors. For a manufacturer, this means that the numbers in which a given projector is sold will be smaller than they would be if there were only cartridges of a single type. The reduction of the numbers in which a given projector is sold increases the cost thereof. The same remarks are applicable to appliances which may be alternatively used to record on or reproduce from magnetic tape. Numerous types of cartridges have already been proposed for such magnetic tape-handling appliances. It is an object of the invention to eliminate these disadvantages and to provide an appliance in which cartridges of different types can be used.

The invention relates to an appliance for recording and/or reproducing information, particularly a motion picture projector for substandard film, which appliance is adapted to be loaded with cartridges which contain a striplike record carrier on a supply reel, and which appliance is provided with locating and/or fixing means which cooperate with corresponding surfaces of the cartridge and serve to hold the cartridge in a predetermined position on the appliance, and with threading devices for mechanically removing the leading end of the strip from the roll on the supply reel, also with drive means for driving the supply reel, and resides essentially in that the appliance comprises at least one additional locating and/or fixing means for locating and/or fixing cartridges of a different type, which have locating and/or fixing surfaces differing from those of the first-mentioned cartridge, additional drive means for driving the supply reel are provided, one of the drive means cooperates in known manner with a flange of the supply reel whereas the other drive means comprise a mandrel, which is adapted to be introduced in known manner through an opening in the cartridge wall into a central bore of the supply reel, and preferably the striplike record carriers which have been moved through exit openings out of a cartridge of any of the different types are adapted to be guided to common guiding means and recording and/or reproducing means. Within the scope of the invention, the arrangement may be such that the means which are associated with cartridges of the different types, at least the fixing means, are mounted on respective attachments for the appliance, one of which attachments is detachably connected to a base structure which comprises at least part of the transmission.

In such an arrangement, the requirements of the user can easily be met in that the attachment desired by the buyer is mounted on the base structure of the appliance. Hence, the base structure may be made in large numbers so that the cost of the appliance is reduced. If the buyer of an appliance intends to use cartridges of different types, he need no longer procure two different appliances but it will be sufficient for him to have different attachments for use with a single base structure. Alternatively, the appliance may be integral and be designed so that cartridges of different types may be fixed to the appliance in one and the same area and the drive means for use with cartridges of a given type are adapted to be removed when a cartridge of another type is to be used.

With that arrangement, the cartridge may be relatively small. A difficulty may arise because the threading device is not always aligned with the exit opening of the cartridge or the center of the reel in the cartridge where cartridges of different type are used. These difficulties may be eliminated within the scope of the invention in that the fixing means are so arranged that the centers of the reels having different capacities are substantially disposed on one and the same line regardless of the type of cartridge which is used. In this connection, the centers of the reels need not actually be disposed on one line, provided that they are substantially disposed thereon. The above-mentioned difficulty may alternatively be avoided in that the appliance is provided with sensing means for detecting the type of cartridge fixed to the appliance. In a development of the invention, the sensing means may control a displaceable carriage, on which the threading device is mounted and which is arranged to be controlled in response to the type of cartridge detected by the sensing means so that the threading means is always aligned with the exit opening of the cartridge.

In another arrangement used to accomplish that object, the pivot of the lever is adjustable to at least two positions, one of which represents an optimum for cartridges of a first type and the other an optimum for cartridges of a second type.

The means for locating cartridges of different types will generally have to be different. These locating means may comprise apertures or projections, which are provided on the cartridge and which cooperate with complementary elements provided on the appliance. Because cartridges of different types have substantially the same main dimensions, the locating means are provided on the appliance generally in the same area and a cartridge of a given type to be mounted on the appliance may interfere with the means for locating cartridges of the second type. To eliminate these difficulties, it is a feature of the invention that the means for locating cartridges of a first type are rigid in the direction in which cartridges of said type are applied to the appliance and are movable in the direction in which cartridges of the second type are applied to the appliance.

Within the scope of the invention, the appliance may be designed to have cartridges of different type mounted thereon in different areas and be provided in each of said areas with fixing means and drive means for cartridges of the associated type. This arrangement will eliminate the difficulties which are due to the provision of different drive means in a single area. In such an appliance, different recording and/or reproducing means may be associated with different areas for fixing cartridges. Preferably, however, a motion picture projector according to the invention is provided with means for guiding the film to a common lens from the different areas. In an appliance for handling magnetic tape, the guide means may guide the magnetic tape from the different areas to common recording and reproducing means.

Appliances having means for threading the strip may be provided with a threading device in each area which is associated with cartridges of a given type. This feature will contribute to a clear and relatively simple structure of the appliance. Alternatively, the threading means may be common to cartridges of different types and may be movable to positions adjacent to cartridges fixed in different areas. In this case, a single threading device may be used for cartridges of all types, provided that this single threading device is designed for use with cartridges of all types which are contemplated.

To enable an adaptation to openings of different size provided to receive the threading device, it is a feature of the invention to provide for a removal of the leading end of the film from the roll a device which comprises movable film-guiding elements, which are movable into the cartridge and which close free openings which exist between the cartridge wall and the threading device which has been moved into the cartridge.

Further details and advantages of the invention will become apparent from the following description of embodiments shown by way of example in the drawing, in which

FIG. 1 is of a motion picture projector according to the invention for substandard film.

FIG. 2 is an enlarged view showing a detail of a modified projector.

FIG. 3 is a view which illustrates the operation of a feeding device FIGS. 4 and 5 illustrate a modification of FIG. 2, FIG 5 being an elevation viewed from line V-V of FIG. 4.

FIG. 6 is a view which illustrates another embodiment comprising an axially movable reel mandrel.

FIGS. 7 and 8 illustrate another embodiment, FIG. 8 being a circuit diagram of the embodiment of FIG. 7.

FIG. 9 is a view which shows an embodiment of the invention in which cartridges of different types are fixed to the appliances in different areas, which are disposed one behind the other.

FIG. 10 is a view which illustrates a design in which cartridges of different types are secured to different areas disposed one beside the other.

FIG. 11 is a top plan view showing the design of FIG. 10.

FIG. 12 is a special embodiment of a threading device in a view which is similar to that of FIG. 11.

FIGS. 13-15 show different means for controlling a threading device.

FIGS. 16 and 17 show means for locking two mode control switches, which are provided for two fixing areas.

FIG. 18 is a view which shows a similar design provided with electrical means.

FIG. 19 is a view which shows a mode control switch which is suitable for use with different cartridge-fixing areas.

FIG. 20 is a view which shows another design in which a part which carries the fixing means can be connected to the projector.

FIG. 21 is a view which shows a motion picture projector according to the invention for substandard film, which projector is provided with an attachment for use with cartridges of one type.

FIG. 22 is an elevation showing part of the projector provided with a different attachment.

FIG. 23 is a perspective view showing the top of the base structure of an appliance according to the invention.

FIG. 24 and 25 show different embodiments according to the invention.

FIGS. 26 and 27 are coordinated views showing a cartridge-mounting device of a motion picture projector for substandard 8-mm. film and a cartridge of a first type (Type A).

FIGS. 28, 29 are similar views for cartridges of a second type (Type B).

FIG. 30 is a view which shows another embodiment with a Type A cartridge.

FIG. 31 is a view which shows the same embodiment with a Type B cartridge.

FIG. 32 is a view which shows a motion picture projector for substandard film provided with a cartridge selector switch.

FIGS. 33 and 34 show details of said embodiment viewed in the directions indicated by arrows XXXIII and XXXIV, respectively, in FIG. 32.

Cartridges 2, 3 of different type can be fixed to a motion picture projector 1 for substandard film. A threading device 4 is movable into the exit opening of cartridge 2 or cartridge 3. The cartridges 2, 3 differ not only in external configuration. Cartridge 2 is provided in one end wall with an opening, not shown, through which a friction wheel 5 may be entered, which is mounted on a lever 6 that is pivoted on a pivot 7. The friction wheel 5 is adapted to be driven by means which are not shown and serves to drive the supply reel in the cartridge 2. For this purpose, the friction wheel engages an end flange of said reel.

The cartridges 3 are not provided with such opening in an end wall but adjacent to the center 8 of the supply reel in such cartridge have an aperture through which a reel mandrel can extend, which is mounted on the projector 1. The center 10 of the reel in the cartridge 2 is not adjacent to the reel mandrel 9 and the cartridge 2 has no aperture for receiving the reel mandrel 9. It will be understood that for the use of cartridges 2 the reel mandrel 9 must be removed from the area of the cartridge whereas the friction wheel 5 must be swung out where car-

tridges 3 are to be used. These remarks will also be applicable if film reels not accommodated in cartridges are to be used instead of the cartridges 3. It will be understood that the illustrated projector 1 may be used with cartridges 2, 3 as well as with reels which are not accommodated in cartridges.

FIG. 2 illustrates an arrangement for a mutual control of the respective drive means. The reel mandrel 9 is mounted on a reel-carrying arm 11, which is pivoted on a pivot 12, to which a cam 13 is fixed. The cam 13 is operatively connected by a tension spring 14 to a push rod 15, which is guided by a pin-slot arrangement. The push rod 15 is provided at its end with a stop 16. In dependence on the position of the push rod 15, the stop 16 is in register with a complementary stop 17 carried by the pivoted arm 6 for the friction wheel 5 or releases said stop 17. A compression spring 18 urges the pivoted arm 6 against a pin 20, which extends through a slot 19 of the pivoted arm 6. The pin 20 is secured to an actuating rod 21, by which the pivoted arm 6 can be released and moved to its operative position.

In the position shown, the reel-carrying arm 11 is in position of rest and the push rod 15 is in its right-hand position, in which the stops 16, 17 are out of register so that the friction wheel 5 can be swung into a cartridge 2a.

If a cartridge 3 or 3a is secured to the appliance, the reel mandrel 9 is required to drive the supply reel in such cartridge. In this case, the reel-carrying arm 11 is swung in the counterclockwise sense and the cartridge 3 or 3a is mounted on the reel mandrel 9. During a pivotal movement of the reel-carrying arm 11, the cam 13 displaces the push rod 15 to the left so that the stop 16 is in register with the stop 17 and the friction wheel 5 cannot be pivotally moved even when it has been released by the actuating rod 21.

FIG. 2 shows also the centers 8, 8a and 8b of cartridges which differ in size and are of a type which is similar to cartridges 3 and 3a. The centers 8, 8a, 8b are disposed on a sector 22 of a circle, which has a radius which is equal to the distance between the centers of the pivot 12 and the reel mandrel 9. The centers 10, 10a, 10b, and 10c of reels accommodated in cartridges which are similar to cartridges 2, 2a lie on a straight line 23. The sector 22 and the line 23 are selected so that the centers of the reels differing in capacity lie virtually on a single line for cartridges of each of the types which are used and are only slightly spaced from said line. This arrangement will ensure that the threading device 4 is always in register with the exit opening of the cartridge regardless of the type and size thereof.

FIG. 3 shows different means for disabling the friction wheel 5. A sensor 25 detects apertures 24 of the cartridges 3. The sensor 25 comprises a sensing pin 26, which is disposed adjacent to the apertures 24 and secured to an arm 28, which is pivoted on a pin 27 and constantly biased by a spring. The arm 28 carries a locking pin 30, which in the inoperative position of the arm 28 extends into the path of the pivoted arm 6 for the friction wheel 5.

If a cartridge 2 which has no aperture 24 is secured to the appliance, the cartridge 2 will depress the sensing pin 26 to move the locking pin 30 out of the path of the pivoted arm 6 so that the latter can be swung in by means of the actuating rod 21. As a cartridge 3 rather than a cartridge 2 is applied to the appliance, the sensing pin 26 will enter aperture 24 and the locking pin 30 will remain in the path of the pivoted arm 6 to lock the same. It will then be impossible to impart a pivotal movement to the arm 6 even by an erroneous operation of the actuating rod 21.

In the embodiment shown in FIG. 2, the centers 8, 8a, 8b or 10 to 10c are disposed substantially on a single line to ensure that the threading device 4 is always in register with the exit opening of the cartridge which is used. A different arrangement for the same purpose is shown in FIGS. 4 and 5. Cartridges 2, 2a and 3, 3a are secured to the projector in such a position that the lower right corner of each cartridge is disposed at the same point. As a result, the centers of the exit openings disposed on the underside of the cartridge will be in-

creasingly displaced to the left as the size of the cartridges increases. To center the threading device 4 on the exit opening of the cartridge which is used, the threading device is mounted on a carriage 31, which is guided on columns 32, 33 and provided with a rack 34 having skew teeth. A compression spring 35 urges the carriage 31 toward stops 36, 37, which are normally engaged by the carriage 31, also as cartridges 2 or 3 are applied to the appliance 1. The threading device 4 will be properly positioned to enter the exit openings of cartridge 2 or 3 when the carriage 31 is in engagement with stops 36, 37.

A sensing lever 38 is urged by a spring 39 out of the wall of the projector. The sensing lever 38 is connected to a toothed sector 40 having skew teeth. As a cartridge 2a or 3a having a larger capacity is applied to the projector 1, said cartridge will turn the sensing lever 38 in the counterclockwise sense in FIG. 5 so that the toothed sector 40 engages the rack 34. As the sector 40 meshes with the rack 34, the carriage 31 is displaced against the action of the spring 35 to align the threading device 4 with the exit opening of cartridge 2a or 3a. A sensing lever 41 having a toothed sector 42 is provided for cartridges having a capacity which is between the capacity of cartridges 2, 3 and the capacity of cartridges 2a, 3a. The sensing lever 41 and sector 42 are similar in function to the sensing lever 38 and sector 40. It will be understood that the free end of the sensing lever 41 protrudes less from the projector housing than the free end of the sensing lever 38. Besides, the sector 42 extends over a smaller angle than the sector 40 so that the application of a medium-size cartridge to the projector 1 will displace the carriage 31 to the left by a smaller distance than the application of a cartridge 2a, 3a having a very large capacity.

Different means for interlocking two reel-driving means are shown in FIG. 6. In this embodiment, the reel mandrel 9 is axially displaceable and is urged by a spring 43 to its operative position, in which the reel mandrel 9 is driven by a belt 44 and a belt pulley 45, which is secured to the stub shaft of the mandrel. When the reel mandrel 9 is in operative position, the belt 44 is trained around a drive pulley 46. As a cartridge having no aperture for the reel mandrel 9 is applied to the appliance, the reel mandrel is axially displaced against the action of the spring 43 so that the belt 44 is moved onto an idler pulley 47 and the reel mandrel 9 is deenergized as soon as it reaches its inoperative position. The position of the reel mandrel 9 is sensed by a sensing lever 48, which engages the free end of the stub shaft of the mandrel. A spring 49 urges the sensing lever 48 into engagement with a disc 50, which is connected to the stub shaft of the reel mandrel 9. The sensing lever 48 is rigid with a shaft 51, to which a locking lever 52 is secured, which extends into the path of a locking cam 53 when the reel mandrel 9 is in operative position. The locking cam is connected to a hollow shaft 54, which at its other end carries the pivoted arm 6 provided with the friction wheel 5. From a drive shaft 55, which is coaxial with the hollow shaft 54, the friction wheel 5 is driven by drive wheels, which are mounted inside the pivoted arm 6. An arm 56 is connected to the hollow shaft 54 and biased by a spring 57. When the locking lever 52 extends into the path of the locking cam 53, the spring 57 cannot rotate the hollow shaft 54. Upon an axial displacement of the reel mandrel 9 to its inoperative position, the sensing lever 48 and the locking lever 52 are pivotally moved in a counterclockwise sense so that the hollow shaft 54 and the pivoted arm 6 are released for a rotation under the action of the spring 57.

It will be understood by a person skilled in the art that different means may be used to disable the means for driving the reel mandrel and that such different means may comprise, e.g., a jaw clutch or an electric switch which is operated by the movement of the reel mandrel. Besides, different means may be used to lock the two drive members 9 and 5.

In the embodiment shown in FIG. 7, the different cartridges are secured in one and the same area, in a carriage 58, and the means for driving cartridges of different types are provided in different areas. In the embodiment shown by way of example,

the carriage 58 is movable from its inoperative position, shown in the drawing, along a rail 59 to different drive means arranged one behind the other. The rail 59 is mounted in a recess in the wall of the projector 1. A displacement to the left moves the carriage 58 first to a position adjacent to the reel mandrel 9. If a cartridge 3 is contained in the carriage 58, the sensing pin 26 will fall into the aperture 24 (see FIG. 3) in the cartridge 3 so that the carriage 58 is also locked in the correct position. If a cartridge 2 having no aperture 24 is contained in the carriage 58, the sensing pin 26 will be depressed so that the carriage 58 can move as far as to the friction wheel 5. The carriage 58 need not be moved from an inoperative position to different drive stations but may be movable between the driving station which is associated with the friction wheel 5 and the driving station which is associated with the reel mandrel 9.

In moving to the several drive stations, the carriage 58 moves in succession over two push buttons 60, 61 for respective switches 60a, 61a, by which the proper drive member 5 or 9 is energized. The corresponding circuit diagram is shown in FIG. 8. The appliance is energized for its various functions by a main switch 62. A normally closed switch 26a is included in the circuit and connected to the sensing pin 26. When the carriage 58 is loaded with a cartridge 3 and displaced to the left in FIG. 7, the sensing pin 26 falls into the aperture of the cartridge 3 and holds the switch 26a closed. The switch 60a is closed at the same time by the pushbutton 60. The reel mandrel 9 is now ready for operation.

When the carriage 58 is loaded with a cartridge 2, the switch 60a is closed by the pushbutton 60 and the switch 26a is open. The means for driving the reel mandrel 9 cannot be energized when the carriage 58 is in this position. Only when the carriage 58 reaches the position associated with the cartridge 2 is the switch 61a closed by the pushbutton 61 so that the means for driving the friction wheel 5 are ready for operation.

In the embodiment shown in FIG. 8, the means for fixing the cartridges 2a, 3a are provided in different areas of the appliance. The cartridges 2a, 3a lie one behind the other with mutually facing end faces. A suitable threading device 63 or 64 is associated with each type of cartridge. Whereas a separate lens could be provided for each type of cartridge, it will be more desirable to provide means, not shown, for guiding film which has been threaded out of the cartridge 2a or 3a to a common lens or a common film gate 65. A separate mode control switch I or II is provided for cartridges of each type.

FIGS. 10 and 11 show an appliance in which means for fixing cartridges of different types are provided in different areas, which are disposed one beside the other. A stripper 68, which is pivotally movable about a pivot 67, which may be stationary, and a film-driving means 69, are provided for cartridges 3a, which are fitted on a reel mandrel 9, which is mounted on a reel-carrying arm 66. A stripper 70 and a film-driving means 71 are provided for cartridges 2a. A simpler arrangement regarding the threading devices is shown in FIG. 12. The two threading devices 72 and 73 are similar and mounted on a common operating lever 74, which is pivotally movable about a pivot 75 by pressure applied to a pushbutton 76. Because the threading devices 72 and 73 are similar, they must be designed so that each threading device can be used with cartridges of both types. An advantage resides in that a single actuating mechanism and a single drive means are required for both threading devices 72, 73. It will not be detrimental if the threading device 73 is also driven when the threading device 72 is used and vice versa.

The embodiment shown in FIG. 13 comprises only a single threading device 77 for cartridges of both types. The device 77 is movable by a cam mechanism to the cartridge 2 or 3. The cam mechanism might consist of suitably shaped camwheels but in the embodiment shown by way of example comprises a cam slot 78, which is designed so that the threading device 77 is moved to the exit opening of the respective cartridge 2 or 3. It will be understood that such a simple cam slot 78 may be used only for cartridges of two types. The threading devices

which are shown, such as the threading device 77, cannot only be displaced into and out of the exit opening of the cartridge but can also be moved axially so that the stripper and the film-driving means are moved out of the path of the film when the same has been threaded out. This arrangement will prevent damage to the film by frictional contact with parts of the threading device.

In the embodiment shown by way of example, a pinion 79 is connected to the drive shaft of the threading device 77. By a spring, not shown, the threading device 77 is normally held in a position facing the cartridge 3. By means of the pinion 79 the threading device can be moved against the action of said spring to the position from which it can be introduced into the cartridge 2. In projectors which are controlled by a program control system, this operation may be accomplished, e.g., in such a manner that when a cartridge 3 is used the starting of the projector initiates immediately the threading operation whereas when a cartridge 2 is used an additional program is initiated which causes a rotation of the threading device 77 by means of the pinion 79.

Another control arrangement for a threading device is shown in FIG. 14 and is substantially similar to the arrangement shown in FIGS. 10 and 11. Cam slots 80, 81 which merge into a common slot 82 are provided to guide a threading device. A deflector 83 is provided between the cam slots 80 and 81 and pivoted on a pivot pin 84. Two sensing members 85, 86 engage the top of the deflector 83 and in response to the application of a cartridge 2 or 3 move the deflector to one position or the other. One of the sensing members 85 and 86 may be replaced by a spring 87, which normally holds the deflector 83 in a given position, in which e.g., the cam slot 80 is exposed. In this case, the sensing element 86 may be omitted and the deflector will be pivotally moved to expose the cam slot 81 only when the sensing member 85 is operated by the application of a cartridge 3.

In the embodiment shown in FIG. 14, the lens of the projector is desirably disposed in the middle between the two cartridges indicated at 2 and 3. This results in the difficulty that the film which has been moved out of the cartridge must be offset transversely to its longitudinal edge. This difficulty may be eliminated in that the cartridges 2 and 3 are mounted on a carriage which can be centered over the lens. Another arrangement is shown in FIG. 15, where the cartridges of different types converge toward their exit openings and a single threading device 88 is shown for cartridges 2, 3 of different types. The threading device 88 is mounted on an actuating lever 89, which is pivotally movable through an angle which is equal to the angle α included by the center lines 90, 91 of the cartridges 2, 3. The threading device 88 is preferably disposed approximately at the intersection of the two center planes 90, 91 so that a small angle is sufficient for the pivotal movement of the actuating lever 89 and the threading device 88.

It is shown in FIG. 9 that different mode control switches I and II may be associated with fixing means disposed in different areas and used to fix cartridges of different types. To prevent an improper operation of these switches I and II, they are normally locked by means shown in FIG. 16. In the embodiment shown by way of example, these means comprise a detent rod 92, which in the zero position of the two switches I and II is in register with a notch 93 in a disc 94 and the position of which is controlled by a sensing device. The sensing device comprises a sensing member 96, which is displaceable against the action of a spring 95 and operated by the wall of a cartridge 2 or 3 as the latter is applied. The sensing member 96 comprises a beveled surface 97, which cooperates with the detent rod 92. When no cartridge is secured to the projector, the inside surface of a slot 98 provided in the detent rod 92 near one end thereof engages the sensing member 96 and the other end of the detent rod 92 engages the notch 93 in the disc 94. The latter is mounted on the shaft of the mode control switch I, so that the latter is normally locked. As a cartridge 2 or 3 is applied to the appliance in the proper area, the sensing member 96 is displaced to the left in FIG. 17 and the beveled

surface 97 displaces the detent rod 92 to release the mode control switch I. A device which is similar to that described for the mode control switch I is provided also for the mode control switch II.

FIG. 18 shows an embodiment in which the sensing member 96 operates a switch, which normally enables the mode control switch I. In this case, the sensing member 96 is disposed only adjacent to the cartridges 3. Only as a cartridge 3 is applied to the projector is the sensing member 96 actuated to shift the switch 99 to a position enabling the mode control switch II.

The use of two different mode control switches for two different fixing areas of the appliance is not essential. FIG. 19 shows a single mode control switch, which may be used to start one drive means and the other. For this purpose, the mode control switch 100 is rotated in direction I or direction II. To prevent a wrong operation of the mode control switch 100, locking pawls 101, 102 are provided, which cooperate with respective ratchet wheels 103, 104. The locking pawls 101, 102 are controlled by the sensing members 96 and tension cords or the like means 105, 106 and ensure that the mode control switch 100 can be rotated in direction I or II only if a cartridge 2 or 3, respectively, is applied to the appliance. The actuating handle of the mode control switch 100 may be axially displaceable for a return of the switch 100 to its zero position. Such return may alternatively be enabled by a means for disengaging the pawls 101 or 102.

Only two different drive stations can be controlled by the mode control switch 100 which is shown. In an appliance for use with cartridges of a larger number of types, the mode control switch would have to be axially displaceable and rotatable.

FIG. 20 shows an embodiment which comprises either of two different insert structures 107 and 108 for cartridges of different types. Each of said insert structures comprises means 109 or 110 for fixing cartridges of the respective type. To prevent confusion, the projector is provided with different connectors 111 and 112 for the insert structures 107 and 108, respectively. In the embodiment shown by way of example, the connectors 111, 112 comprise connector pins carried by the projector although such pins may alternatively be carried by the insert structures. In the latter case, the connector pins may cooperate with sensing means to enable the respective reel-driving means or the like. Because the pins of the connectors 111 and 112 are spaced different distances apart, the apertures for receiving said pins may be provided in the projector in one and the same area if the pins are provided on the inserts 107 and 108. This arrangement would be similar to that shown in FIGS. 1 and 2. Similarly, the projector could be designed as shown in FIG. 20 and a single insert structure could be provided which carries the fixing means 109 and the fixing means 110.

In the embodiment shown in FIGS. 21 to 23, the projector 1 comprises a base structure 1² connected to an attachment 1³. The latter carries fixing means, not shown, for cartridges 114 or 114a of a given type. The attachment 1³ also comprises a threading device, which is specially designed for use with the cartridges 114, 114a and which comprises a stripper 68 and a film-threading device 69. In FIG. 21, the stripper 68 is shown broken away to illustrate the transmission disposed below the stripper. The attachment 1³ comprises also a belt drive, which comprises a belt 107 driving a pulley 108, which is mounted on the pivot 109 of the reel-carrying arm 11. At its other end, the arm carries the mandrel 9 for the reel disposed in cartridge 114 or 114a. The reel mandrel 9 is driven from the pulley 108 by means which are not shown. The belt 107 is driven by a friction wheel 124, which has a shaft 113 that is mounted in a projection of a housing which encloses the attachment 1³. Behind the friction wheel 124, the shaft 113 carries a belt pulley driving the belt 107. Pins 114, 115 are connected to the attachment 1³ and enter holes provided in the housing of the base structure 1² so that the attachment of the appliance is centered on the base structure 1².

The attachment 1³ of the appliance 1 comprises that portion of the appliance which has been described. The base structure 1² accommodates the remaining part of the appliance. Of said remaining part, FIG. 21 shows only a clutch 116 and the means for driving the spindle 117 for the take-up reel of the projector 1.

The clutch 116 comprises a driving friction wheel 118, which drives the friction wheel 124 of the attachment 1³. The friction wheel 124 drives a further friction wheel 119 for a drive belt 120, which is trained over a deflecting pulley 121, which is mounted in a projection of the housing of the base structure 1². The driving wheel 118 drives also a friction wheel 122, which in turn drives the threading drive 69.

FIG. 22 shows an embodiment which comprises a base structure 1² and another attachment 123, which is intended for use with cartridges 2a of a type which differs from cartridges 114, 114a. The attachment 123 comprises a threading device which is particularly suitable for use with cartridges 2a and which includes a stripper 124 and a film-threading drive 126. Instead of the reel mandrel 9 provided in the attachment 1³, the attachment 123 comprises a friction wheel 127, which is carried by an arm 129, which is pivoted on a pivot 128. A belt 130 is provided to drive the friction wheel 127 and drives a pulley 131, which is mounted on the pivot 128 and by means of another belt 132 drives a belt pulley 133. The belt 130 is again driven by a belt pulley which is mounted on the same shaft as a friction wheel 134. This friction wheel 134 corresponds to the friction wheel 124 of the attachment 1³. For the sake of clearness, only the driving wheel 118 of the clutch 116 of the base structure 1² is shown in FIG. 22. FIG. 22 shows also an actuating rod 135, which is mounted in the base structure 1² of the appliance 1 and protrudes from the housing of that base structure into the housing of the attachment 123. The actuating rod 135 may be used to impart a pivotal movement to the arm 129 so that the friction wheel 127 can enter the cartridge 2a through an opening in the end of the cartridge 2a and can then engage a flange of the reel in said cartridge to drive said reel.

Another friction wheel 136 is provided in the base structure 1² of the appliance 1 and serves to drive the threading device 125, 126. As the attachment 123 is applied to the base structure 1² of the appliance 1, the friction wheel 136 engages a friction wheel 137, which is mounted in the attachment 123. The threading device 125, 126 is carried by an actuating lever 138, which is pivotally movable about a pivot 139 in response to pressure applied to a sensing member 140. A belt pulley 141 is mounted on the pivot 139 and is driven from wheel 137 by a belt 142. The driving wheel 143 of the threading drive 126 is driven from the belt pulley 141 by means of a belt 144, which is trained over a deflecting pulley 145 mounted on the actuating lever 138.

The attachment 123 comprises pins 146, 147 which correspond to the pins 114, 115 of the attachment 1³. Besides, FIG. 22 shows a projection 148 of the housing of the base structure 1², that projection extends into a suitable recess in the housing of the attachment 123 and serves also to center the attachment.

FIG. 23 shows the top of another base structure 149 of an appliance according to the invention. That appliance is provided with quick-acting connecting means 150, which cooperate with complementary means provided on the attachment and enable a quick separation and application of the attachment from and to the base structure of the appliance. The base structure 149 of the appliance is accommodated in a housing which surrounds the base structure not only on the outside but also closes the same at the top by a top wall 151. In this way, the means in the housing are protected against being soiled and damaged in storage and shipment. For an improved centering, the top of the housing of the base structure 149 comprises a boxlike top extension 152, which has walls which are somewhat inclined inwardly and tend to center the attachment as it is applied to the base structure 149.

A take-off shaft 154 extends through an aperture 153 in the wall 151 and serves to transmit power from the base structure 149 of the appliance to attachments. The take-off shaft 154 is provided at its free end with a quick-acting coupling 155, which in the embodiment shown by way of example consists of a plug coupling, which has a central quadrangular hole 156 and a somewhat inclined surface leading to said hole so that this coupling is also self-centering. The extension 152 has such a height that it protrudes over the shaft 154 and the coupling 155 and assists in preventing damage to the shaft 154. The same remark is applicable to the actuating rod 158 extending through an aperture 157 in the wall 151 and corresponding to the actuating rod 135 in FIG. 22. For a reliable guidance of the take-off shaft 154 and the actuating rod 158, bearings for the shaft 154 and rod 158 are provided at the apertures 153 and 157. Of these bearings, only a bearing 159 for the take-off shaft 154 is shown.

FIGS. 24 and 25 show a different arrangement, which accomplishes the same object as the arrangement shown in FIGS. 4 and 5. Two cartridges 2 and 3 of different types, namely, Type A and Type B, are located by locating means, not shown, in such a manner that the lower right corner of all cartridges will be at the same point whereas the locations of the reel centers will differ greatly. In the drawing, the position of the reel centers of Type A cartridges are indicated at A₁ to A₄. A₁ is the position of the center of a cartridge for 15 meters of film, A₂ the position of the center of a cartridge for 30 meters of film, A₃ the position of the center of a cartridge for 60 meters of film and A₄ the position of the center of a cartridge for 120 meters of film. The positions of the centers of Type B cartridges are indicated at B₁ to B₄. It will be apparent that the centers of the large cartridges are so widely spaced that a common pivot for the lever which carries the threading device could not be located at such a point that an optimum path for the threading device will be obtained. To avoid these difficulties, the lever 207 which carries the threading device is not mounted on a stationary pivot but on a pivoted lever 208. A two-armed lever 214 is provided to shift the threading device and is pivoted on the pivotal axis 215 of lever 208. The lever 214 carries a sensing member 216 at one end and at the other end bears on the lever 207 by means of an interposed spring 217. A spring 218 urges the lever 208 to its inoperative position shown in solid lines in FIG. 24. A notch 219 formed in the lever 214 cooperates with a pawl 220, which is biased by a spring 221 and controlled by means of a push rod 222 from the arm 223 which guides the film to the take-up reel 212. A depression of the sensing member 216 causes the lever 214 to interlock with the pawl 220 holding the lever 214 in operative position, indicated in dotted lines in FIG. 24. The spring 217 bears on the lever 207 and tends to impart a pivotal movement thereto in the counterclockwise sense. The spring 224 which is secured to the lever 207 and to the lever 208 transmits said pivotal movement to the lever 208 so that the center 225 of the deflecting roller 226 of the belt drive 225 describes a path defined by an arc of a circle a. This shift of the threading device will be induced by the application of a Type A cartridge. A stop 227 is disposed adjacent to the lever 208 and guided on a shaft 228 parallel to the pivotal axis 215 of the lever 208. By means of a knob 229, the stop can be axially moved into and out of the plane of the lever 208. When a Type B cartridge is used, the knob 229 is shifted to move the stop 227 into the plane of the lever 208. An operation of the sensing member 216 imparts a pivotal movement to the lever 207 as described hereinbefore. This pivotal movement will be transmitted by the spring 224 to the lever 208 until the latter engages the stop 227 and then can no longer follow the movement of the lever 207. The latter is now pivotally moved about the axis 230 and imparts to the center 225 of the pulley 226 for the friction belt a movement along an arc of a circle. That arc is indicated at b and optimally approaches the centers of the reels for Type B cartridges.

As soon as the threading operation has been completed and the leading end of the film has reached the take-up reel 212 and is being wound up on the same, the tensioned film acts on the film-guiding arm 223 and tends to impart to said arm a pivotal movement in the counterclockwise sense so that the pawl 220 is lowered to release the two-armed lever 214, which is now returned by the spring 218 to its inoperative position. The levers 207 and 208 are now moved in a clockwise sense so that the spring 224 and the stop 231 carried by the lever 207 finally engage the lever 208. Now the threading mechanisms are again in their inoperative position shown in solid lines in FIG. 24. The film-guiding arm 223 associated with the take-up reel 212 is controlled by means of the mode control switch 213, which has a shaft that carries a cam 232, which by means of a push rod 233 imparts a pivotal movement to the film-guiding arm 223. The belt drive 205 of the threading device is driven by a driving belt 234, which is deflected by a pulley 235 mounted on the common pivot of levers 207 and 208.

FIG. 25 shows two modifications of the appliance just described. A main difference concerns the means for shifting the threading device. The pivot 215 for the lever 208 carries a gear 236, which is connected to a grooved pulley, around which the belt 234 is trained which serves to drive the threading device. The gear 236 is in mesh with an idler gear 237, which is mounted on a pivoted plate 238, which is biased in a counterclockwise sense by a spring 239 to hold the gear 237 in mesh with a gear 240, which is mounted on a stationary axis and is driven in a counterclockwise sense by the drive motor, not shown, of the appliance. An extension 241 of the plate 238 bears on a bell-crank lever 242, which carries a pushbutton 243 and which is held by a spring 244 in the position shown in solid lines in FIG. 25. An extension 245 of the bell-crank lever is in register with a pivoted pawl 246, which is biased by a spring 247 and which like the pawl 220 in the embodiment of FIG. 24 is controlled by the film-guiding arm 223 associated with the take-up reel. To initiate the threading operation, the pushbutton 243 is depressed so that the bell-crank lever 242 interlocks with the pawl 246, the pivoted plate 238 is released and the idler gear 237 is swung in the counterclockwise sense into engagement with the gear 240. The latter is now operatively connected to the gear 236. A one-armed lever 249 is pivoted to the shaft 215. A friction clutch 248 is provided between the gear 236 and the one-armed lever 249. As soon as the operative connection to the friction wheel 236 has been established, the friction clutch 248 imparts to the lever 249 a movement in the clockwise sense. The lever 249 bears on the lever 207 and imparts to the latter and to the lever 208 a pivotal movement in the clockwise sense. If the stop 227 is disposed in the plane of the lever 208, the center 225 of the wheel 226 describes the path *a*.

FIG. 25 illustrates another modification of the means controlling the threading device. The bell-crank lever 242 may be replaced by a push rod 250, which engages the pivoted plate 238 and which is controlled by a cam mounted on the shaft of the mode control switch. In other respects the threading device has the function described hereinbefore.

Other embodiments may be adopted. For instance, the stop 227 may be controlled by a sensing member, which cooperates with surfaces that are provided on cartridges and typical of the type of cartridge so that the stop 227 is retracted from the plane of the lever 208 as a Type A cartridge is applied.

The appliance 1 shown in FIGS 26 to 29 comprises means for locating and fixing Type A and Type B cartridges. These means consist of a rib 302, which is rigid with the appliance and which cooperates with complementary stops carried by the cartridges and takes up the forces which are transmitted to the cartridge during the operation of the reel therein. A friction wheel 5 is provided to drive a film reel 303 disposed in a Type A cartridge 2 and can be pivotally moved into the cartridge 2 through an opening 205 in the housing of said cartridge. The walls of a Type B cartridge 3 are provided with apertures 308, 309, which are coaxial with the reel and

through which the reel mandrel 9 can be inserted. In this case, the reel mandrel 9 is detachably mounted on the projector 1 and is removed when a Type A cartridge is to be used.

The rib 302 which is rigid with the appliance cooperates with stops 319 that are provided on cartridges of both types. The remaining locating means are specific to each type of cartridge. The means for locating Type A cartridges comprise a plate 311, which is pivoted on a shaft 312, which is rigid with the appliance. The offset plate 311 carries two upwardly directed extensions 313 and 314, which are in register with corresponding apertures 315 and 316 in the cartridge. A spring 317 biases the plate 311 against a stop 318 to hold the plate 311 in an operative position. The cartridges 2 are applied to the appliance from above in a slightly inclined direction and are aligned on the appliance by the extensions 313, 314 and corresponding apertures 315, 316 in the cartridge. A stop 319 of the cartridge engages the rib 302 which is rigid with the appliance. A Type B cartridge is to be applied in the direction of the axis of the reel mandrel 9. In this case, the wall of the cartridge strikes against the extensions 313 and 314 so that a pivotal movement to the rear about the shaft 312 is imparted to the plate 311 (see FIGS. 28 and 29). The locating means also comprise a lever 321, which is pivoted on shaft 320 and carries a pin 322, which is parallel to the axis of shaft 320. A spring 323 biases the lever 321 in the counterclockwise sense against a pin 325, which is rigid with the appliance. Type B cartridges are provided adjacent to the pin 322 with an aperture 324, which in conjunction with the pin 322 ensures an alignment of the cartridge on the appliance. As a Type A cartridge is mounted, the cartridge wall strikes on the pin 322 and imparts to the latter and to the lever 321 a pivotal movement in the clockwise sense in FIGS 26 and 27. This will ensure that an application of a cartridge of one type will move the means for locating cartridges of the other type to an inoperative position. It will also be ensured that the means for locating a cartridge of a given type cannot yield so that they will hold the cartridge exactly in position.

In the arrangement shown in FIGS. 30, 31, a lever 405 carries a friction belt drive 405 and a stripper 404. The lever 405 is mounted on a stationary axis in the appliance and corresponds, e.g., to the levers 207, 208 of FIGS. 24, 25. The belt drive 403 is driven by a belt 406. The stripper 404 is displaceably mounted and is biased upwardly by a spring 415. For this purpose, the lever 405 carries a U-shaped member 412, on which the stripper 404 is slidably guided. The displacement of the stripper 404 is limited by a stop, not shown. A lever 413 is pivoted to the U-shaped member 412, which is biased by a spring 414 tending to impart to the lever 413 a pivotal movement in the clockwise sense to the position shown in solid lines in FIG. 30. The cartridge 2 is provided at its base and in its right-hand side wall with an opening through which the belt drive 403 and the stripper 404 can be moved into the cartridge. In the zone designated 416, the opening of the cartridge is wider than the film whereas the opening has a smaller width in the zone 417, where only the belt drive can be introduced and the film cannot be moved out of the cartridge in this zone. To thread the leading end of the film out of the cartridge, the lever 405 is swung upwardly so that initially the stripper 404 engages the film roll 407. The stripper 404 is then pushed back against the action of the spring 415 until the belt drive 403 engages the film roll (this position is indicated in dotted lines in FIG. 30). As the stripper 404 is moved into the cartridge, the lever 413 strikes against the wall of the cartridge and is swung down to close the free opening between the cartridge and the stripper for the film.

FIG. 31 shows the threading device of the appliance loaded with a Type B cartridge 3. This cartridge differs substantially from Type A cartridges in that it is open not only at the bottom but also at both side walls. Besides, the zone 416 in which the opening is wider than the film is much larger. As the threading device is moved into the cartridge, the lever 413 remains substantially in its initial position so that a leading end of the film when disposed behind the stripper in the clockwise

sense will be deflected toward the inside wall of the cartridge and cannot emerge therefrom behind the stripper. When the roll of film has rotated through about 270°, the leading end of the film reaches the belt drive 403 and is moved between the latter and the film roll 407 and finally stripped off by the film stripper 404 to move out of the cartridge in the passage defined between the stripper 404 and the belt drive 403. With the same advantages, this design may be used in appliances for use with cartridges of only one type. In this case too, a closing of the free openings of the cartridge during the threading operation will be desirable and will considerably improve the reliability of the appliance in operation. These free openings are indispensable for reasons of tolerance.

FIGS. 32-34 show an arrangement which has been described in part in connection with FIGS. 26-31. Corresponding parts carry the same reference characters as in the above-mentioned FIGS. The embodiment shown in FIG. 32-34 differs from that of FIGS. 26-31 mainly in the provision of a cartridge selector switch 515 at the top of the appliance.

The cartridge selector switch 515 is mounted on a shaft 516 to be pivotally movable and axially displaceable. The switch 515 is guided by an aperture 517 of the projector housing. The aperture 517 comprises a long slot 517a, which is normal to the axis of shaft 516. A spring 518 tends to move the selector switch 515 in the clockwise sense. The selector switch 515 is connected to the lever 6, which at its free end carries the friction wheel 5. This friction wheel is driven by a belt drive 521 and by additional drive means, which are not shown. The lever 6 carries also an extension 520, which is in register with a push rod 522 and with the plate 311, which is pivoted on a pivot 312. The push rod 522 is provided with slots 525, 526, with which the rod is guided on stationary pins 527, 528. The push rod 522 is forced by a spring 529 against a cam 530, which is mounted on the shaft of the mode control switch 213. When the switch 213 is rotated in the counterclockwise sense from the position shown in FIG. 32, the push rod 522 will fall into the recess 531 of the cam 530 to release the lever 6. If the selector switch 515 is in the position shown in solid lines in FIG. 33, the spring 518 will impart to the lever 6 a pivotal movement in the clockwise sense until the friction wheel 5 engages the periphery of the flange of the film supply reel. The operation of the friction wheel 5 is initiated at the same time so that the film supply reel is driven in the clockwise sense at high speed and the film is rewound on said reel. If the selector switch 515 was in the position indicated in dash-dot lines in FIG. 33, the spring 518 can pivotally move the switch 515 only through a small angle because the slot 517 has only a small depth and the friction wheel 5 is locked in its inoperative position when the selector switch 515 is in this position. In a desirable embodiment of the invention, the extension 520 of the lever 6 now engages the plate 311 so that an axial displacement of the switch 515 will impart to the plate 311 a pivotal movement out of the path of the cartridge against the force of a spring 317. In this position of the selector switch 515, cartridges of the second type can be applied. When the cartridges of that type are applied to the appliance in the direction of the arrow 537 in FIG. 34 and the selector switch 515 is in the position indicated in solid lines in FIG. 33, the side wall of the cartridge will strike against the extensions 313 and 314 of the plate 311 and will pivotally move the latter to the rear. In another embodiment of the invention, this shift may be utilized for a direct operation of the cartridge selector switch in response to the application of a cartridge of one type or another. In this case, it will be sufficient to provide a positive connection between the plate 311 and the cartridge selector switch.

Another cam 538 is mounted on the shaft of the mode control switch 213 and in register with a push rod 539. The latter has at one end a slot 540, which is guided on a stationary pin 541, and at the other end is pivoted to a crank 542, which is pivoted on a shaft 543. A spring 544 biases the push rod 539 against the cam 538. A gear 545 is mounted on the cam 542 and in mesh with a gear 546, which is rotatably mounted on

the shaft 543. The gear 546 is connected to a pulley 547, around which the drive belt 406 is trained, which drives the belt drive 403. The gear 545 is also in register with a gear 548, which is mounted on a stationary axis and which is constantly driven by the drive motor of the appliance. A pivotal movement of the mode control switch 213 in the clockwise sense causes the push rod 539 to enter the recess 549 of the cam 538. As a result, the cam 542 is pivotally moved in the counterclockwise sense until the gear 545 establishes an operative connection between the gear 548 and the gear 546. The drive belt 406 can now drive the belt drive 403. By means of the friction clutch 550, which is diagrammatically shown, the gear 546 drives also the lever 405 in the counterclockwise sense to move the belt drive 403 and the stripper 404 into the cartridge through the opening 416 in the base thereof. When the threading operation has been completed, the mode control switch 213 is rotated one step in the clockwise sense so that the push rod 539 is lifted out of the recess 549 of the cam 538. The operative connection to the gear 546 is thus interrupted so that the belt drive is arrested and a spring, not shown, returns the lever 405 to its initial position.

The invention is not restricted to the examples shown and described hereinbefore because numerous modifications are possible within the general concept of the invention as defined in the claims.

What is claimed is:

1. An information-processing appliance for use with a striplike information carrier wound on a reel which is contained in a cartridge of either of first and second types, each of said cartridges having locating and fixing surfaces specific to the type of cartridge, said reel in the cartridges of said first type having a flange, said reel in the cartridges of said second type having a central bore, said cartridges of said second type having a wall formed with an aperture aligned with said bore, said information carrier on said reel having a leading end, said appliance comprising first locating and fixing means engageable with said locating and fixing surfaces of any cartridge of said first type so as to hold said cartridge of said first type in an operative position on said appliance, second locating and fixing means engageable with said locating and fixing surfaces of any cartridge of said second type so as to hold said cartridge of said second type in an operative position on said appliance, threading means operable to mechanically move said leading end of said information carrier from said reel in a cartridge of either of said first and second types when said cartridge is held in said operative position, first reel-driving means adapted to cooperate with said flange and operable to drive said reel in a cartridge of said first type when said cartridge is in said operative position, and second reel-driving means comprising a mandrel adapted to extend through said aperture into engagement with said bore of a reel of a cartridge of said second type when said cartridge is in said operative position, said second reel-driving means being operable to drive said reel in said cartridge of said second type.
2. An appliance as set forth in claim 1, which comprises means for recording information on said information carrier.
3. A appliance as set forth in claim 1, which comprises means for reproducing information recorded on said information carrier.
4. An appliance as set forth in claim 1, which is a motion picture projector for substandard film.
5. An appliance as set forth in claim 1, which comprises transducing means for processing information, and guide means for guiding said information carrier along a predetermined path to said transducing means, said threading means being operable to move said leading end of said information carrier from cartridges of either of said first and second types to said guide means.

6. An information-processing appliance for use with a striplike information carrier wound on a reel which is contained in a cartridge of either of first and second types, each of said cartridges having locating and fixing surfaces specific to the type of cartridge, said reel in the cartridges of said first type having a flange, which appliance comprises
- a base structure including main drive means, an attachment detachably mounted on said base structure and comprising locating and fixing means adapted to cooperate with said locating and fixing surfaces of any cartridge of said first type to hold said cartridge of said first type in an operative position on said appliance, threading means operable to mechanically move said leading end of said information carrier on said reel in a cartridge of said first type when said cartridge is in said operative position, and
- reel-driving means operatively connected to said main drive means and adapted to cooperate with said flange and operable to drive said reel in a cartridge of said first type when said cartridge is in said operative position.
7. An appliance as set forth in claim 6, which comprises quick-acting means connecting said attachment to said base structure.
8. An appliance as set forth in claim 6, in which said base comprises a base housing, said attachment comprises an attachment housing, and connecting means are provided which protrude from at least one of said base and attachment housings and connect said attachment to said base.
9. An appliance as set forth in claim 8, in which said base housing comprises a box and said attachment housing comprises a cover interfitted with said box.
10. An appliance as set forth in claim 9, in which said main drive means comprise a part protruding from a part of said base housing, said reel-driving means comprise a part protruding from a part of said attachment housing, and said box and cover protrude over said protruding parts of said main drive means and reel-driving means.
11. An appliance as set forth in claim 8, in which said base housing is provided with a base housing aperture, said attachment housing is provided with an attachment housing aperture aligned with said base housing aperture, each of said base and attachment housing apertures is provided with coupling guide means, and said connecting means comprise a coupling, which connects said main drive means to said reel-driving means and is guided by coupling guide means.
12. An appliance as set forth in claim 8, in which said connecting means are self-centering.
13. An appliance as set forth in claim 6, which comprises means for centering said base and attachment relative to each other.
14. An appliance as set forth in claim 6, in which said attachment comprises said reel-driving means.
15. An information-processing appliance for use with a striplike information carrier wound on a reel which is contained in a cartridge of either of first and second types, each of said cartridges having locating and fixing surfaces specific to the type of cartridge, said reel in the cartridges of said second type having a central bore, said cartridges of said second type having a wall formed with an aperture aligned with said bore, said information carrier on said reel having a leading end, which appliance comprises
- a base structure including a main drive means, an attachment detachably mounted on said base structure and comprising locating and fixing means adapted to cooperate with said locating and fixing surfaces of any cartridge of said second type to hold said cartridge of said second type in an operative position on said appliance,

- threading means operable to mechanically move said leading end of said information carrier on said reel in a cartridge of said second type when said cartridge is in said operative position, and
- 5 reel-driving means operatively connected to said main drive means and comprising a spindle adapted to extend through said aperture into engagement with said bore of a reel of a cartridge of said second type when said cartridge is in said operative position, said second reel-driving means being operable to drive said reel in said cartridge of said second type.
16. An appliance as set forth in claim 15, which comprises quick-acting connecting means connecting said attachment to said base structure.
17. An appliance as set forth in claim 15, in which said base comprises a base housing, said attachment comprises an attachment housing, and connecting means are provided which protrude from at least one of said base and attachment housings and connect said attachment to said base.
18. An appliance as set forth in claim 17, in which said base housing comprises a box and said attachment housing comprises a cover interfitted with said box.
19. An appliance as set forth in claim 18, in which said main drive means comprise a part protruding from a part of said base housing, said reel-driving means comprise a part protruding from a part of said attachment housing, and said box and cover protrude over said protruding parts of said main drive means and reel-driving means.
20. An appliance as set forth in claim 17, in which said base housing is provided with a base housing aperture, said attachment housing is provided with an attachment housing aperture aligned with said base housing aperture, each of said base and attachment housing apertures is provided with coupling guide means, and said connecting means comprise a coupling, which connects said main drive means to said reel-driving means and is guided by said coupling guide means.
21. An appliance as set forth in claim 17, in which said connecting means are self-centering.
22. An appliance as set forth in claim 15, which comprises means for centering said base and attachment relative to each other.
23. An appliance as set forth in claim 15, in which said attachment comprises said reel-driving means.
24. An appliance as set forth in claim 1, in which said first and second locating and fixing means are disposed substantially in one and the same area and each of said first and second reel-driving means are adapted to be selectively disabled for the use of the appliance with cartridges of said second and first types, respectively.
25. An appliance as set forth in claim 24, for use with cartridges of said first and second types, the cartridges of each of said types including cartridges having different capacities, in which appliance
- 50 said first and second fixing and locating means are arranged so that the centers of said reels of cartridges of different capacities of each of said first and second types lie substantially on one and the same line.
26. An appliance as set forth in claim 24, which comprises sensing means for detecting the type of a cartridge held in said operative position on the appliance.
27. An appliance as set forth in claim 26, for use with cartridges having an exit opening for said information carrier, in which appliance
- 55 said threading means are mounted on a slidable carriage and
- 60 means are provided which in response to the detection of a cartridge type by said sensing means move said carriage to such a position that the threading device will be directed to the exit opening of a cartridge of either of said
- 70

- first and second types when said cartridge is held in said operative position.
28. An appliance as set forth in claim 26, in which said said sensing means comprise said mandrel.
29. An appliance as set forth in claim 24, which comprises a lever carrying said threading means, a shifting member carrying a pivot on which said lever is pivoted, said fixing and locating means being adapted to hold a cartridge of either of said first and second types in said operative position so that said reel is centered on an axis which is parallel to the axis of said pivot, said shifting member being movable between first and second positions, which are respectively optimized for cartridges of said first and second types.
30. An appliance as set forth in claim 29, in which said lever means comprise pivotally connected first and second arms, said first arm carries said threading device, said arms carry first stop means limiting the relative pivotal movement of said first and second arms, spring means are connected to said first arm and tend to move said first arm to an inoperative position, shifting means are connected to said first arm and operable to move said first arm against the action of said spring means, and stationary second stop means are provided which are engageable by said second arm in response to an operation of said shifting means.
31. An appliance as set forth in claim 30, which comprises stop control means for moving said second stop means out of the path of said second arm.
32. An appliance as set forth in claim 31, in which said stop control means comprise a cartridge selector switch.
33. An appliance as set forth in claim 32, in which said threading means comprises a threading drive including an idler wheel, said shifting means comprise a shifting lever and a frictional clutch which bears on said shifting lever and is arranged to impart a pivotal movement to said lever so as to move said first arm against the force of said spring means in response to an operation of said idler wheel.
34. An appliance as set forth in claim 33, in which said shifting lever is coaxial with said idler wheel.
35. An appliance as set forth in claim 33, which comprises disengageable means for driving said idler wheel.
36. An appliance as set forth in claim 35, which comprises a pawl tending to lock said disengageable means in an engaged position and means for rendering said pawl inoperative in a predetermined condition of said appliance.
37. An appliance as set forth in claim 36, which comprises sensing means engageable by said information carrier and arranged to render said pawl inoperative in response to the engagement of said sensing means with said information carrier.
38. An appliance as set forth in claim 37, which comprises a take-up reel for said information carrier, said take-up reel having a hub, a guiding arm which is movable between an inoperative position and an operative position and in the latter position is adapted to guide said leading end of said information carrier to said hub and to move to said inoperative position in response to tension imparted to said information carrier as the latter is wound up on said take-up reel, said guiding arm being arranged to render said pawl inoperative when said guiding arm is in said inoperative position.
39. An appliance as set forth in claim 24, which comprises a lever carrying said threading means, first and second pivots, said lever being adapted to be pivoted on each of said first and second pivots,

- said fixing and locating means being adapted to hold a cartridge of either of said first and second types in said operative position so that said reel is centered on an axis which is parallel to the axes of said first and second pivots, and selecting means are provided for selectively pivoting said lever on either of said first and second pivots.
40. An appliance as set forth in claim 39, in which said selecting means comprise a cartridge selector switch.
41. An appliance as set forth in claim 39, which comprises shifting means for shifting said lever and a pawl for locking said shifting means in an operative position.
42. An appliance as set forth in claim 41, which comprises sensing means engageable by said information carrier and arranged to render said pawl inoperative in response to the engagement of said sensing means with said information carrier.
43. An appliance as set forth in claim 42, which comprises a take-up reel for said information carrier, said take-up reel having a hub, a guiding arm which is movable between an inoperative position and in the latter position is adapted to guide said leading end of said information carrier to said hub and to move to said inoperative position in response to tension imparted to said information carrier as the latter is wound up on said take-up reel, said guiding arm being arranged to render said pawl inoperative when said guiding arm is in said inoperative position.
44. An appliance as set forth in claim 39, in which said selector means comprise sensing means for detecting the type of the cartridge held in said operative position on the appliance.
45. An appliance as set forth in claim 24, in which each of said first and second reel-driving means are movable between an inoperative position and at least one operative position.
46. An appliance as set forth in claim 45, in which said first reel-driving means comprise a friction wheel which is engageable with said flange in said operative position and the axis of said friction wheel has the same orientation in said operative and inoperative positions of said first reel-driving means, and said mandrel is adapted to engage said bore in said operative position and the axis of said mandrel has the same orientation in said operative and inoperative positions of said second reel-driving means.
47. An appliance as set forth in claim 46, which comprises means for moving said friction wheel to an inoperative position in response to a movement of said mandrel to its operative position and for moving said friction wheel to its operative position in response to a movement of said mandrel to said inoperative position.
48. An appliance as set forth in claim 45, in which said mandrel is retractable from said operative position out of said bore and aperture to said inoperative position.
49. An appliance as set forth in claim 48, which comprises a spring which urges said spindle to said operative position.
50. An appliance as set forth in claim 48, which comprises means for de-energizing said second reel-driving means in response to the movement of said mandrel to said inoperative position.
51. An appliance as set forth in claim 24, in which said appliance is arranged to have cartridges of said first type applied thereto in a first direction and to have cartridges of said second type applied thereto in a second direction, which differs from said first direction, and said first locating and fixing means are rigid in said first direction and movable in said second direction.
52. An appliance as set forth in claim 51, which comprises spring means urging said first fixing and locating means to an operative position.
53. An appliance as set forth in claim 51, in which said fixing and locating means are pivotally mounted, and

said first fixing and locating means are pivoted on an axis which is normal to said second direction.

54. An appliance as set forth in claim 1, in which said fixing and locating means are mounted on a carriage which is movable along a predetermined path and said first and second reel-driving means are disposed adjacent to and spaced along said path.

55. An appliance as set forth in claim 54, which comprises sensing means for detecting the type of the cartridge mounted on said cartridge and for locking said cartridge in position adjacent to said first reel-driving means when the fixing and locating surfaces of a cartridge of said first type are engaged with said first fixing and locating means and for locking said carriage adjacent to said second reel-driving means when said fixing and locating surfaces of a cartridge of said second type are engaged with said second fixing and locating means.

56. An appliance as set forth in claim 54, in which said carriage is movable to an inoperative position in which it is adapted to have a cartridge applied to said fixing and locating means.

57. An appliance as set forth in claim 54, which comprises means for initiating the operation of said first reel-driving means in response to a movement of said carriage whereby a cartridge of said first type having its fixing and locating surfaces engaged with said first fixing and locating means is moved to an operative position adjacent to said first reel-driving means and means for initiating the operation of said second reel-driving means in response to a movement of said carriage whereby a cartridge of said second type having its fixing and locating surfaces engaged with said second fixing and locating means is moved to an operative position adjacent to said second reel-driving means.

58. An appliance as set forth in claim 54 for use with cartridges having exit openings, in which appliance said first fixing and locating means are disposed on said carriage in a first area, said second fixing and locating means are disposed on said carriage in a second area, which is spaced from said first area, said threading means comprise a threading device which is adapted to cooperate with cartridges of said first and second types, and said carriage is movable to a first position in which said exit opening of a cartridge of said first type held in said operative position faces said threading device, and to a second position in which said exit opening of a cartridge of said second type held in said operative position faces said threading device.

59. An appliance as set forth in claim 58, which comprises sensing means for detecting the presence of a cartridge in one of said areas and for moving said carriage to said first position in response to the detection of a cartridge in said first area and to said second position in response to the detection of a cartridge in said second area.

60. An appliance as set forth in claim 1, in which said first fixing and locating means and said first reel-driving means are disposed in a first area and said second fixing and locating means and said second reel-driving means are disposed in a second area, which is spaced from said first area.

61. An appliance as set forth in claim 60, for use with cartridges having narrow end faces, in which appliance said first and second areas are disposed one behind the other and each of said fixing and locating means are adapted to hold the respective cartridge in said operative position in one of said areas so that an end face of said cartridge faces toward the other of said areas.

62. An appliance as set forth in claim 60, for use with cartridges having broadsides, in which appliance said first and second areas are disposed one beside the other and

each of said fixing and locating means are adapted to hold the respective cartridge in said operative position in one of said areas so that a broadside of said cartridge faces toward the other of said areas.

5 63. An appliance as set forth in claim 62, in which said threading means comprise a threading device which is adapted to cooperate with cartridges of said first and second types and selectively movable to said first and second areas.

10 64. An appliance as set forth in claim 63, which comprises cam means for guiding said threading device to said first and second areas.

65. An appliance as set forth in claim 64, in which said cam means comprise cam slot means.

15 66. An appliance as set forth in claim 65, in which said cam slot means comprise a common cam slot portion, a first cam slot portion leading from said common cam slot portion to said first area, a second cam slot portion leading from said cam slot portion to said second area, said common, first and second cam slot portions defining a junction, and in which a movable deflector is mounted adjacent to said junction and adapted to guide said threading device selectively from said common cam slot portion to said first and second cam slot portions.

20 67. An appliance as set forth in claim 64, which comprises sensing means for detecting the presence of a cartridge in one of said areas and for operating said cam means to guide said threading device to the area in which said cartridge is held.

30 68. An appliance as set forth in claim 63, for use with cartridges having exit openings, in which appliance

said first fixing and locating means are adapted to hold a cartridge of said first type in an operative position so that said cartridge extends along a first predetermined plane to said exit opening,

25 said second fixing and locating means are adapted to hold a cartridge of said second type in an operative position so that said cartridge extends along a second predetermined plane to said exit opening,

30 said first and second predetermined planes converge towards said exit openings, and said threading device is pivotally movable between first and second positions, in which it is aligned with said first and second planes, respectively.

35 69. An appliance as set forth in claim 68, in which said first and second planes intersect and said threading device is movable to an inoperative position, in which it is disposed at the intersection of said planes.

70. An appliance as set forth in claim 63, which comprises means tending to move said threading device to a position adjacent to one of said first and second areas and program-controlled means for moving said threading device to a position adjacent to the other of said first and second areas.

71. An appliance as set forth in claim 70, which comprises sensing means for detecting a cartridge held in an operative position in said other area, said program-controlled means being arranged to move said threading device to a position adjacent to said other area in response to the detection by said sensing means of a cartridge held in an operative position in said other area.

72. An appliance as set forth in claim 58, in which said threading means comprise

60 a first threading device associated with said first area and a second threading device associated with said second area.

73. An appliance as set forth in claim 72, in which said first and second threading means are coaxial and common actuating means are provided, which are operable

65 to move one of said first and second threading means into a cartridge of said first or second type, respectively, which is held in said operative position on said appliance.

74. An appliance as set forth in claim 58, which comprises first and second mode control switches associated with said 70 and second areas, respectively.

75. An appliance as set forth in claim 74, in which said mode control switches are normally disabled and which comprises sensing means for detecting a cartridge held in an operative position in said first and second areas and for enabling one of said mode control switches in response to the detection of a cartridge held in an operative position in the area associated with said mode control switch. 5

76. An appliance as set forth in claim 74, in which one of said mode control switches is normally enabled and the other of said mode control switches is normally disabled, and 10

sensing means are provided to detect a cartridge held in an operative position in the area associated with said normally disabled mode control switch and arranged to disable said normally enabled mode control switch and to enable said normally disabled mode control switch in response to such detection. 15

77. An appliance as set forth in claim 58, which comprises a mode control switch associated with said first and second areas. 20

78. An appliance as set forth in claim 77, in which said mode control switch is selectively movable to a first set of positions associated with said first area and to a second set of positions associated with said second area and said first and second sets of positions are disposed on opposite sides. 25

79. An appliance as set forth in claim 77, in which said mode control switch comprises an actuating member which is rotatable and axially movable. 30

80. An appliance as set forth in claim 77, in which said mode control switch is movable to a first set of positions associated with said first area and a second set of positions associated with said second area and sensing means are provided to detect a cartridge held in an operative position in one of said first and second areas and to block a movement of said mode control switch to positions other than those associated with an area in which a cartridge is thus detected. 35

81. An appliance as set forth in claim 58, which comprises a base structure comprising a main drive means, 40 a detachable carrier carrying said first and second fixing and locating means and said first and second reel-driving means, a first coupling adapted to connect said main drive means to said first reel-driving means, and 45 a second coupling, which is different from said first coupling and adapted to connect said main drive means to said second reel-driving means, each of said first and second coupling comprising a first element which is comprised in said base structure and a second element which is carried by said carrier and engageable with said first element of the same coupling. 50

82. An appliance as set forth in claim 1, in which said threading means are movable into a cartridge held in said operative position and to define gaps with a cartridge into which they have thus been moved, and 55 guiding means for the information carrier in provided, which are adapted at least partly to close said gaps.

83. An appliance as set forth in claim 82, in which said guiding means are hinged to said threading means and spring means are provided which urge said guiding means away from said threading means. 60

84. An appliance as set forth in claim 83, in which said threading means comprise reel-contacting means adapted to contact said information carrier on said reel and 65

said guiding means are hinged to said reel-contacting means.

85. An appliance as set forth in claim 83, for use with cartridges having a wall defining an exit opening, in which appliance 70

said threading means comprise a friction drive for engaging said information carrier on said reel and a stripper for stripping said leading end from said reel, said stripper 75

having a free end portion adapted to engage said information carrier on said reel, said guiding means comprise an element which is hinged to said free end portion and said spring means urge said element against said wall.

86. An appliance as set forth in claim 1, which comprises a cartridge selector switch movable between a first position, in which said switch disables said one of said reel-driving means, and a second position, in which said switch enables said one reel-driving means.

87. An appliance as set forth in claim 86, in which said first reel-driving means comprise a friction wheel, which is movable between an inoperative position, in which it is disengaged from said flange of a cartridge of said first type held in said operative position, and an operative position, in which it is engaged with said flange and operable to drive said reel, and locking means are provided, which are adapted to lock said friction wheel in said inoperative position when said cartridge selector switch is in said first position and to release said friction wheel for movement to said operative position when said cartridge selector switch is in said second position.

88. An appliance as set forth in claim 87, in which said friction wheel is mounted on a support member operable to move said friction wheel between said inoperative and operative positions, said support member is biased by spring means urging said friction wheel to said operative position,

a mode control switch is provided, which is movable to a plurality of positions and by a movement to at least one of said positions is adapted to operate said support member against the action of said spring means to move said friction wheel to its inoperative position, said cartridge selector switch comprises a lever, which is connected to said support member, and cam means which cooperate with said lever and permit of a movement of said lever and said support member when said cartridge selector switch is in one of its first and second positions and which hold said lever and support member in position when said cartridge selector switch is in the other of its first and second positions.

89. An appliance as set forth in claim 86, which comprises a first carrier carrying said first fixing and locating means and movable between an inoperative position, and an operative position, in which a cartridge of said first type having fixing and locating surfaces engaged with said first fixing and locating means is in an operative position, a second carrier carrying said second fixing and locating means and movable between an inoperative position and an operative position, in which a cartridge of said second type having fixing and locating surfaces engaged with said second fixing and locating means is in an operative position, and

means operatively connecting said cartridge selector switch to said first and second carriers and arranged to move said first carrier to said operative position and said second carrier to said inoperative position in response to a movement of said cartridge selector switch to one of its first and second positions, and to move said first carrier to said inoperative position and said second carrier to said operative position in response to a movement of said cartridge selector switch to the other of its first and second positions.

90. An appliance as set forth in claim 1, which comprises a main drive means, a first carrier carrying said first fixing and locating means and said first reel-driving means, a second carrier carrying said second fixing and locating means and said second reel-driving means, a first coupling adapted to connect said main drive means to said first reel-driving means, and

a second coupling, which is different from said first coupling and adapted to connect said main drive means to said second reeledriving means.

91. An appliance as set forth in claim 90, which comprises sensing means for detecting a cartridge of either of said first

and second types held in said operative position and for engaging said first coupling in response to a detection of a cartridge of said first type and for engaging said second coupling in response to a detection of a cartridge of said second type.
